UNITED STATES PATENT OFFICE.

NICHOLAS MEROLA, OF LOS ANGELES, CALIFORNIA.

AUTOMOBILE SIGNAL.

Application filed May 14, 1925. Serial No. 30,337.

This invention relates to signal apparatus and more particularly to vehicle signals.

An object of the invention is to provide a simple, compact device for effectually displaying a tail-light signal, a stop signal, and right and left hand turn signals. Another object is to provide a "still" stop signal and a moving turn signal, and to provide a turn signal which gives differential colored lights, different from the stop signal.

An object is to provide a motor actuated, pendulum member having the differential turn signal means, and in this connection, to provide for the operation of the signal by fluid pressure derived from a pressure chamber of the motor.

Other objects and advantages will be manifest in the following specification of an embodiment of the invention here illustrated, modifications, variations and adaptations being deemed within the scope of the invention as it is here claimed.

Figure 1 is a perspective of the signal device. Figure 2 is a vertical section of the signal device. Figure 3 is a section and diagrammatic view of the apparatus; the master valve being in "right turn" signal action position. Figure 4 is a sectional detail of the pendulum motor valve. Figure 5 is a schematic section showing the relief or exhaust position of the motor valve.

The signal comprises a suitable shell having an upper tail-light box 2 with a face glass 3 covering a bulb 4 having a circuit 5. The box 2 is superjacent a larger chamber 6 and extends down into it for compactness of structure.

This chamber has a front glass 7 marked "Stop" so as to comply with the laws or ordinances requiring such designation, and in the chamber is a bulb or bulbs 8 on circuit 5.

The bottom of the chamber 6 has a slot which preferably is flanged at 9-9 to provide a guide allowing a swinging action of a pendulum stem 10 having at its bottom a signal lamp 11.

This lamp has lenses 12-13 lettered "R" and "L" and under these is a partition 14 dividing the lamp 11 into two separate parts having the bulbs 15-15^a. These, or the lenses, may be of different color so that the contrast may be utilized to the more effective giving of the desired differential left and right turn signals.

The stem 10 is pivotally mounted at 16

and is adapted to be swung to and fro by any desired means. Such means is here shown as including a fluid motor including a cylinder 17 having a double action piston 18 to opposite ends of which pressure fluid is served by a suitable valve member 18' in a valve body 19 having a pressure port line 20 and an opposite open exhaust port 21, (Figure 4). Intermediate these are opposite conduits 22-23 to opposite ends of the cylinder 17. The valve 18 is of diametrical form and is connected by its lever 24 and link 25 to the pendulum 10.

When the pendulum is hanging straight down the valve 18 is held in the position seen in Figure 4, and uncovers port 22 and supply 20 but covers port 23 this the latter now being open to the exhaust side 21.

If now the pressure fluid is turned into line 20 pressure will pass to port 22 and act to thrust the piston to the right; this action, by a piston rod roller 28, pressing the pendulum over to one side and starting oscillations. On this stroke of the pendulum the valve 18 closes conduit 22 to pressure and opens it to exhaust, and opens conduit 23 to pressure from line 20. Hence the piston is reversed by pressure, and by gravity on the pendulum. Motor operation continues as long as the pressure is applied. It is understood that the piston rollers 28 will be so spaced as to permit of effective action of the pendulum.

Pressure supply is controlled by a suitable valve means which I prefer to mount upon the steering column P of the vehicle so as to be very convenient for the driver. Light signals are concurrently turned on. This is done by the master valve means controlling the signal motor.

The master valve includes a block 30 having bolts 31 enabling it to be firmly clamped upon the post P. The block has a supply tube 32 from any source of pressure (or conversely to a vacuum chamber). Opposite the supply is attached the pressure line 20 of valve 18-19. Between the lines 20-32, of block 30, is an open exhaust port 33, which may be shielded to deflect the exhaust stream, if desired.

In the block 30 is a valve plug 34 having ducts 35-36 leading to a recess 37 always open to line 32. Between ducts 35-36 is a passage 38, (Figure 5), which in one position of plug 34 connects line 20 to the exhaust 33 of block 30 so that as the pendulum

10 drops to the vertical position the piston 18 can freely find a neutral or intermediate position. This is when the driver turns the valve 34 to normal, non-signal position 5 which is done by means of a handle 40 of the valve.

This handle works on a segment 41 having a central detaining portion 42 and end contacts 43-44 which are electrically in circuit with respective signal bulb 15-15^a. The handle has an insulated feed line contact 45 to engage either terminal 43-44 and thus complete the signal lamp circuit when the handle is thrown to the limit at 15 either end of the segment 41 and in such action opening line 20 by either duct 35-36 to pressure line 32 and starting the signal motor from the neutral position of piston.

Bringing the handle 40 to center cuts off 20 flow and opens the motor to exhaust 33. This permits the pendulum lamp 11 to drop to vertical where it is lightly retained by a spring seat 48 to prevent undesired vibration of the signal.

25 The piston rod is preferably supported in a guide 50 and has rollers 28 to actuate the pendulum.

The lamp 11 has pointed, opposite side windows 11^a-11^b showing lights of the same 30 color as their respective sides of the lamp 11.

When the vehicle is to be stopped the still, "stop" signal 7 is energized by closing its circuit switch, which is usually connected to the foot brake. When the vehicle is to 35 be turned, the handle 40 is snapped by the driver's finger to right or left, as intended turn, and this starts the signal and turns on the proper signal light in lamp 11.

The movement of the turning signal will 40 be an indication to those following, that the car will not stop but keep moving to make the turn.

The port 33 is in the same plane as the lines 20-32 and passage 38 crosses below 45 duct 36 but its ends extend up to the plane of port 33. For clarity, Fig. 5 shows the plug 34 sectioned in the plane of the passage 38 and as lifted into the plane of the lines 20-32.

50 What is claimed is:

1. A vehicle signal device including a pendulously operating sign, a reciprocating actuator engaging a part of the sign, an actuator action reversing valve device connected to the sign, and a master controlling means for the actuator.

2. A vehicle signal device including a pendulously operating signal element, a reciprocating double-action fluid motor whose 60 piston operatively engages said element, a motor reversing valve connected to the said element, and which is automatically brought to a neutral pressure relief position by said element and a remote supply valve connected to the reversing valve.

3. A vehicle signal device including a pendulously operating signal element, a reciprocating double action fluid motor whose piston operatively engages said element, a motor reversing valve connected to the said 70 element, and which is automatically brought to a neutral pressure relief position by said element and a remote supply valve connected to the reversing valve, the supply valve having a relief port to allow the actuator 75 to come to neutral position.

4. A vehicle signal including a shell having a tail-light box, a "still" stop light signal, and a pendulous oscillatory, turning signal means provided with oppositely pointing 80 darts.

5. A vehicle signal including a shell having an oscillatory, pendulous turning signal means; said turning signal being of different color from the stop signal means including a lamp box having oppositely pointing window compartments with differently colored media.

6. A stop light signal shell having a slotted bottom, a pendulum pivoted in the shell 90 and oscillating in the slot, a motor piston rod in the shell engaging and for oscillating the pendulum, and a motor valve connected to the pendulum.

7. A stop light signal shell having a slotted bottom, a pendulum pivoted in the shell and oscillating in the slot, a double action motor in the shell engaging and for oscillating the pendulum, a local valve connected to the pendulum; and a pressure fluid main 100 valve for the motor.

8. A stop light signal shell having a slotted bottom, a pendulum pivoted in the shell and oscillating in the slot, motor means in the shell for oscillating the pendulum, a 105 motor governor connected to the pendulum; and a remote master valve for controlling the motor fluid.

9. A stop light signal shell having a slotted bottom, a pendulum lamp pivoted in the shell and oscillating in the slot, means in the shell engaging and for oscillating the pendulum, said means including a pressure fluid operated motor; a motor valve connected to the pendulum, and a remote master 115 valve for controlling the motor fluid.

10. A vehicle signal apparatus including a shell having a pendulum lamp, a fluid motor in the shell having a reversing valve connected to the pendulum, said motor oscillating the pendulum, and a remote master 120 supply and relief valve for the motor.

11. A vehicle signal device including a pendulum stem carrying a set of opposite direction signals illuminable for night service, a motor having a piston rod with rollers engaging the stem of the pendulum, and a valve connected to the stem to control the 125 motor.

NICHOLAS MEROLA.
